UNITED STATES PATENT OFFICE.

WILLIAM T. CHARLES, OF WAYNESBORO, PENNSYLVANIA.

REAMER.

1,109,321.

Specification of Letters Patent.

Patented Sept. 1, 1914.

Application filed October 22, 1913. Serial No. 796,741.

To all whom it may concern:

Be it known that I, WILLIAM T. CHARLES, a citizen of the United States, residing at Waynesboro, in the county of Franklin and State of Pennsylvania, have invented certain new and useful Improvements in Reamers, of which the following is a specification, reference being had to the accompanying drawings.

10 This invention relates to new and useful improvements in tools and, more particularly to a reamer and the primary object of the invention is to provide a device of this character in which a plurality of cutters are provided, capable of various adjustments in the body of the reamer.

A further object of the invention resides in providing cutters which are circular in cross section and provided with improved 20 means for the retention and adjustment thereof in the body of the device.

Still another object of the invention resides in providing a device which is simple and durable in construction, inexpensive to 25 manufacture and one which will be very efficient and useful in operation.

With these and other objects in view, the invention consists in the novel features of construction, combination and arrangement 30 of parts as will be hereinafter referred to and more particularly defined and set forth in the specification and claims.

In the accompanying drawings forming a part of this application, Figure 1 is a plan view of a device constructed in accordance 35 with my invention. Fig. 2 is a side elevation thereof. Fig. 3 is a section as seen on line 3—3, of Fig. 2, looking in the direction of the arrow. Fig. 4 is a similar view as 40 seen on line 4—4, of Fig. 2; and Fig. 5 is a side elevation of one of the cutter members removed.

In describing my invention, I shall refer to the drawings in which similar reference 45 characters designate corresponding parts throughout the several views and in which—

1 indicates a body of substantially cylindrical design, provided at regular intervals therein with the slots or grooves 2, which 50 extend the full length of the same, said slots or grooves being arcuate in cross section. These slots or grooves are designed to receive therein the cutters or blades 3, which are designed circular in cross section and each provided with a longitudinal arcuate groove 4. Portions of these cut-

ters or blades 3 are adapted to project beyond the outer periphery of the block or body 1, and that portion of the groove 4, indicated at 5, forms the cutting edge of each blade or cutter. I have provided improved means for the retention in place of the adjustment of said blades or cutters in the body 1, and to this end, said body is provided at predetermined points therein, with a plurality of threaded radial sockets 6 and alternating said sockets 6 are additional threaded and radial sockets 7. The sockets 6 terminate at their outer ends in recesses 8 and said last mentioned sockets are adapted to receive in engagement therewith the threaded screws 9. The recesses 8 receive the heads of said screws therein and said sockets are so designed as to permit the heads of said screws 9 to contact with the sides of the cutters. In order to permit the heads to properly engage said cutters or blades 3, and not project to a great extent beyond the periphery of the body 1, said cutters or blades are recessed at predetermined points therein as shown at 10.

The screws 9 are disposed on one side of the cutters or blades 3 and in order to aid said screws in retaining said blades or cutters in place, the additional screws 11 are provided, which are engaged with the threaded sockets 7. The head of these latter screws are received in recesses 12 formed in the body at the outer termination of the sockets 7 and said heads which are 90 beveled are adapted to contact with the opposite sides of the cutters or blades 3 from that engaged by the heads of the screws 9. It must here be stated also, that the outer ends of the cutters or blades 3 are beveled 95 as shown at 13, which obviates any necessity of re-grinding the same after the first grinding action thereon. From this construction, it will be seen that the cutters or blades 3 are adapted for axial movement in 100 the grooves or slots 2, whereby the cutting edges of the same may be adjusted, as desired. This adjustment of the cutting edges of the blades or cutters 3 is accomplished by the adjusting of the screws 9 and 11. The 105 device, as shown, for instance, has the cutters thereof disposed to their positions, giving the greatest depth of cut and when it is desired to reduce the depth of the cut, said cutters 3 are turned clockwise in the grooves 110 or channels 2 of the body. In order to accomplish this clockwise movement of the

- cutters 3, the screws 9 and 11 are released from their binding engagement therewith, whereupon said cutters are disposed to approximately the proper adjustment desired.
- 5 The screws 9 are then adjusted inwardly in the body until the same engage the walls of the recesses 2 and the exact adjustment of said cutters may then be made. When the exact adjustment is made, the screws 11 are turned home in binding engagement against the cutters 3, thus securing the same in their effective and adjusted positions. As shown in the drawings, the cutters disposed to their position of the greatest depth of 15 cut, have the cutting edges thereof disposed in registration with the radial line passing through the centers of the body 1 and the cutters 3, as indicated by the line A-B, of Fig. 1. The disposition of these cutters, it is well for me to simply say, which is very effective in use.
- From the foregoing description of the construction of my improved device, the manner of applying the same will be readily understood and it will be seen that I have provided a device which is simple and reliable in construction, inexpensive to manufacture and one which will be very efficient and useful in operation.
- 36 While I have particularly described the characteristic adapted to perform the functions set forth, it is obvious that various changes in form, proportion and in the minor details of construction may be resorted to within the scope of the claim without departing from the spirit or sacrificing any of the principles of the invention.
- Having thus described my invention, what I claim is:
- 40 1. A reamer of the class described comprising a body having a plurality of longitudinal grooves in the sides thereof, a plurality of cutters received in said grooves and projecting beyond the outer faces of said body, said cutters being rotatably adjustable in said grooves, and means for adjustably securing said cutters in position in the body. 45
2. A reamer of the class described comprising a substantially cylindrical body having a plurality of longitudinal grooves in the periphery thereof, a plurality of elongated cutters arranged in said grooves and having portions projecting beyond the periphery of said body, and a plurality of adjusting screws extending radially within the body, said adjusting screws being arranged in series and engaged with opposite sides of each of the cutters to adjustably retain the latter in the grooves of the body. 50
3. A reamer of the class described comprising a substantially cylindrical body having a plurality of arcuate and longitudinal grooves in the periphery thereof, a plurality of substantially cylindrical cutters received 55 in said grooves and having portions thereof projecting beyond the periphery of said body, each of said cutters having a longitudinal groove and a plurality of recesses therein, a plurality of adjusting screws extending radially within the body and adapted for engagement with the opposite sides of the cutters to secure the same in their adjusted positions. 60
4. A reamer of the class described comprising a substantially cylindrical body having a plurality of arcuate and longitudinal 65 grooves in the periphery thereof, a plurality of substantially cylindrical cutters received in said grooves and having portions thereof projecting beyond the periphery of said body, each of said cutters having a longitudinal groove and a plurality of recesses therein, a plurality of adjusting screws extending radially within the body and adapted for engagement with the opposite sides of the cutters to secure the same in their adjusted positions. 70
5. A reamer of the class described comprising a substantially cylindrical body having a plurality of longitudinal grooves in the periphery thereof, a plurality of substantially cylindrical cutters received 75 in said grooves and having portions thereof projecting beyond the periphery of said body, each of said cutters having a longitudinal groove and a plurality of recesses therein, a plurality of adjusting screws extending radially within the body and adapted for engagement with the opposite sides of the cutters to secure the same in their adjusted positions.
- In testimony whereof I hereunto affix my signature in the presence of two witnesses.

WILLIAM T. CHARLES.
